UNITED STATES PATENT OFFICE.

SOREN MADSEN, OF NEW YORK, N. Y.

AUTOMATIC VENDING APPARATUS.

1,137,648.

Specification of Letters Patent. Patented Apr. 27, 1915.

Application filed August 26, 1914. Serial No. 858,736.

To all whom it may concern:

Be it known that I, SOREN MADSEN, a subject of the King of Denmark, residing at New York, in the county of New York and State of New York, have invented certain new and useful Improvements in Automatic Vending Apparatus; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in coin vending apparatus, the object in view being to produce a simple and efficient mechanism whereby commodities may be automatically dispensed by the insertion of the requisite number of coins to coöperate with a push rod to release locking mechanism.

The invention comprises various details of construction, combinations and arrangements of parts which will be hereinafter fully described, shown in the accompanying drawings and then specifically defined in the appended claims.

My invention is illustrated in the accompanying drawings, in which:

Figure 1 is a front elevation of a cabinet forming a part of my invention. Fig. 2 is a central vertical sectional view through the cabinet. Fig. 3 is an enlarged detail in elevation partly in section of the operative parts of the device. Fig. 4 is an enlarged detail view of a spring-pressed tilting locking device, and Fig. 5 is a sectional view on line 5—5 of Fig. 3.

Reference now being had to the details of the drawings by letter, A designates the wall of a cabinet in which is a casing A' having a series of shelves A² dividing the casing into a series of compartments, each adapted to contain any commodity to be dispensed automatically by my apparatus. Said casing has mounted upon the side thereof a bar B provided with a series of notches terminating in shoulders B' with curved portions B² intermediate the shoulders, each shoulder being opposite each compartment in the casing and provided for the purpose of allowing one compartment to be lowered at a time opposite an opening C which is closed by means of a door C' above the shelf C² and

to which opening access may be had to the compartment after it has been lowered to delivery position.

Fastened to the casing by means of a bracket member D, shown clearly in Fig. 2 of the drawings, is a rod D' having a handle D² at its upper end and its lower end a piston D³, which is provided with a by-pass 65, and which piston is adapted to move within the tubular receptacle D⁴, adapted to contain oil or liquid which is designated by letter D⁵, the purpose of said piston working in the liquid being to allow the cabinet to lower gradually after it is released by mechanism which will be herein-after described.

A coin chute, designated by letter E, is mounted at an inclination in the wall of the cabinet and has two complemental parts, 75 designated by letters E' and E'', which are hinged together at E², and each part has an elongated opening E³ therein. The part E' has a shoulder E⁴ formed upon the inner face thereof, forming a track down which the coins inserted in the upper end of the slot are adapted to run to make exit at the lower end thereof into the hopper F, which latter is provided with an inclined bottom F', down which the coin passes into the 85 slotted tilting coin-receiving member H, which is pivotally mounted upon the pivot H' upon the laterally extending bracket arm I which is fastened by means of the bolts I' to the wall of the cabinet. Said member H 90 has a contracted extension H² at its lower end, carrying an anti-friction wheel H³, and J is a spring which is fastened at one end to the wall of the cabinet and its other end to a pin J' carried by the member H and serves to normally hold the latter so that the anti-friction wheel H³ will engage a shoulder upon the bar B to lock the various compartments in a fixed position. Said member H, 95 a detail of which is shown in Fig. 4 of the drawings, is provided with an inclined portion L which, as the coin is dropped from the chute above, is adapted to strike and be directed thereby down through the space intermediate the opposite walls of the member H and to be temporarily supported by the inwardly projecting end N of the stationary supporting bar N'. Said bar N', it will be noted, is provided with a series of apertures N², and O is a bolt passing through one 100 or another of said apertures and also the bracket arm I and provides means for hold-

ing the bar N' in different positions accordingly as it may be desired to adapt the apparatus to operate with one, two or three coins as the case may be. In the drawings I have illustrated the bar N' as adjusted in the center of the three apertures, which adapts the apparatus to operate with two coins which are shown in dotted lines in Fig. 3 and designated by letter R. It will be noted that the angled projection N of the bar N' is adapted to engage the notch or slot Q , shown in Figs. 3 and 4 of the drawings, and to form a temporary support for the coin before the apparatus is actuated for the purpose of dispensing any commodity from one of the compartments.

A push rod T is mounted horizontally in an aperture in the wall of the cabinet and in an aperture in the bracket extension T' , and a coiled spring T^2 is interposed between the bracket arm and the inner face of the casing and tends normally to return the push rod after having been moved to the position shown in dotted lines in Fig. 3. Said push rod, it will be noted, is mounted in alignment with the recess or notch S , formed in the member H , and is adapted to contact with the upper of the two coins for the purpose of causing the member H to tilt to the position shown in the dotted lines to allow the anti-friction wheel H^3 at its lower end to be thrown out of engagement with a shoulder B' formed upon the bar B to allow the casing having the compartments and the notched bar fastened thereto to lower, the downward movement of the casing being checked by the piston and rod before described, making the descent gradual.

The operation of my invention will be readily understood and is as follows:—Access to the various compartments may be had from the rear of the casing in order to fill the same with the different commodities wished to be automatically dispensed. The casing is raised to its highest position by means of the handle end D^2 of the bar D' drawing the piston to the upper end of the tubular shell D^4 . When the device is set to operate by the use of two coins, as shown in the drawings, the coins are dropped in the coin receiving member H and assume the positions shown in Fig. 3, one resting upon the other, the upper of the coins in alignment with the push rod T . By pushing in upon the rod T against the edge of the coins, the latter will cause the member H to tilt to position shown in dotted lines, thus releasing the wheel H^3 from engagement with the shoulder and allowing the casing to lower by gravity gradually incident to the piston pushing down through the oil or liquid in the shell D^4 . When the member H tilts to the position shown in dotted lines in Fig. 3, the laterally projecting end of the bar N' will be out of engagement with the

notch Q , allowing the coins to fall through the lower open end of the member H . Immediately after the wheel H^3 is released from the shoulder B' , the bar B will commence to lower and the spring J will draw the member H back to its normal position, the wheel H^3 riding upon the curved edge B^3 of said bar.

In the event of the apparatus being set to operate with three coins, the pivotal pin O is adjusted in the upper of the three apertures N^2 , making it necessary for three coins to be superimposed one upon another in order to bring the uppermost thereof in alignment with the push rod T .

It will be noted that, by the provision of an apparatus embodying the features of my invention, an automatic vending apparatus is provided, so arranged that each time the member H is tilted through the medium of the push rod the anti-friction wheel H^3 is released and the casing containing the compartments allowed to lower the head of one compartment and this operation may be repeated until access is had to each of the various compartments in order throughout the series and after which the apparatus may be reset by raising the compartment through the medium of the lever as described.

While I have shown in the drawings a single casing, it will be understood that I propose to use a plurality of similarly constructed casings in a single cabinet, duplicating the parts shown and described.

What I claim to be new is:

1. An automatic vending apparatus comprising a casing provided with a coin chute, a movable slotted coin-receiving member into which the coin is directed from the chute, means cooperating with said member for holding one or more coins within the latter, a plunger adopted to contact with a coin exposed in the slot of the member to cause the latter to move, and means upon said member for supporting an article carrying member.

2. An automatic vending apparatus comprising a casing provided with a coin chute, a tilting slotted member adapted to receive a coin from a chute, adjustable means for holding one or more coins within the latter, a spring-pressed plunger adapted to contact with a coin exposed in the slot of the member to cause the latter to tilt, and means upon the lower end of the tilting member for supporting an article carrying member.

3. An automatic vending apparatus comprising a casing provided with a coin chute, a tilting slotted coin-receiving member mounted within the casing, the edge of the latter having notches, an adjustable member supported within the casing and designed to engage said notches to cause the apparatus to operate with one or more coins, a spring-pressed plunger adapted to contact

with a coin exposed in the slot of the member to cause said member to tilt, and means upon the member for supporting an article carrying member.

5 4. An automatic vending apparatus comprising a casing provided with a coin chute, a coin receiving member having a passage-way extending the entire length thereof and open ended and provided with a slot in one 10 edge thereof, an inclined portion within the member for directing a coin toward said slot, the member being provided with notches below the slot, pins projecting from said member and pivotally mounted within the 15 casing, a spring fastened at one end to the member above its pivotal point and its

other end to the wall of the casing, a bar adjustably held within the casing and having a lateral extension for engagement with one of said notches, and a spring-pressed 20 plunger adapted to bear against a coin exposed in said slot to cause the member to tilt, and means upon the tilting member for supporting an article carrying member which is released as the latter tilts. 25

In testimony whereof I hereunto affix my signature in presence of two witnesses:

SOREN MADSEN.
